J. HALL.

SELF STARTING INJECTOR FOR STEAM BOILERS.

APPLICATION FILED NOV. 13, 1919.

1,422,199.

Patented July 11, 1922.

UNITED STATES PATENT OFFICE.

JOSEPH HALL, OF STOCKPORT, ENGLAND.

SELF-STARTING INJECTOR FOR STEAM BOILERS.

1,422,199.

Specification of Letters Patent. Patented July 11, 1922.

Application filed November 13, 1919. Serial No. 337,757.

To all whom it may concern:

Be it known that I, JOSEPH HALL, a British subject, residing at Stockport, county of Chester, England, have invented certain new and useful Improvements in Self-Starting Injectors for Steam Boilers, of which the following is a specification.

This invention relates to improvements in injectors for steam boilers.

10 The object of this improvement is to construct injectors, having a self acting motion for starting and re-starting (automatically), and for the purpose of lifting and forcing water into steam boilers against concussion and vibration, or break-off in the water supply.

15 The invention consists in the particular construction and disposition of the parts comprising a longitudinally sliding nozzle placed above an automatic lifting cone and nozzle to create a vacuum in the overflow chamber, a chamber forming a liquid pressure receiver at the outlet end of the delivery cone and a check valve with water and steam passages through it to facilitate starting and to effect a self closing when the injector is stopped. The invention will be fully described with reference to the accompanying drawing which shows a section 20 through the injector.

25 The injector is provided with a steam inlet A and a water inlet B both of which are provided with control valves not shown on the drawing. The steam inlet A is connected to a nozzle or orifice a screwed into the water inlet B so as to be concentric therewith with an annular water space b around it. The water inlet B is screwed into the main casing C of the injector. Above the steam nozzle a and the water space b is arranged an automatic lifting cone and nozzle D held in position by being screwed on to an annular ring c inwardly projecting from the casing C.

30 The lifting cone and nozzle D is tapered along the greater part of its length but its outlet d is enlarged.

35 The steam nozzle a and the lifting cone D serve to raise water into the injector and for starting or restarting automatically in case of a break in the water supply.

40 A chamber E is formed around the lifting cone D and is connected to the overflow E'.

45 The tubular body F carries in its lower

part a longitudinally sliding nozzle F' arranged vertically above the lifting cone D, and the sliding nozzle F' serves the purpose of creating a partial vacuum in the overflow chamber E and for taking up the overflow water automatically. The top of the cone D 55 serves as a seating for the bottom of the sliding nozzle F'. The delivery cone f through the upper part of the body F is tapered as shown, and opens into a chamber G which acts as a receiver for the water 60 pressure from the delivery cone f thereby facilitating the automatic starting and re-starting of the injector. The upper end of the member F serves as a seat for an automatic check valve H which slides in the 65 upper end of the casing C and closes the chamber G. The check valve H is provided at or near its centre with steam and water passages h h' and with a passage h² in the centre for admitting the boiler pressure in 70 the cap of the injector casing, the boiler pressure being used for automatically forcing down the check valve H on to its seating.

75 The chamber G opens into an annular chamber K surrounding the member F and connecting with the delivery L which is provided with a controlling valve not shown in the drawing.

80 The injector is particularly applicable for use on boilers of locomotives, although it 85 may be used on other types of boilers.

85 What I claim as my invention and desire to protect by Letters Patent is:—

90 In a self-starting injector for steam boilers, the combination with a steam nozzle and lifting cone for raising water into the injector for starting and restarting automatically of a sliding cone placed above the lifting cone to create a partial vacuum in the overflow chamber, a delivery cone, a 95 liquid pressure chamber at the delivery orifice of the delivery cone to facilitate starting and restarting of the injector, and a valve controlled by the pressure of the boiler closing said pressure chamber.

100 In testimony whereof I have hereunto set my hand in presence of two subscribing witnesses.

JOSEPH HALL.
